US00D868799S

(12) **United States Design Patent** (10) Patent No.: **US D868,799 S**
Matsuda (45) Date of Patent: **** Dec. 3, 2019**

(54) **DISPLAY PANEL OR SCREEN WITH GRAPHICAL USER INTERFACE**(71) Applicant: **SONY CORPORATION**, Tokyo (JP)(72) Inventor: **Hazime Matsuda**, Kanagawa (JP)(73) Assignee: **SONY CORPORATION**, Tokyo (JP)(***) Term: **15 Years**(21) Appl. No.: **29/631,452**(22) Filed: **Dec. 29, 2017****Related U.S. Application Data**

(63) Continuation of application No. 29/517,926, filed on Feb. 18, 2015, now Pat. No. Des. 810,094.

(30) **Foreign Application Priority Data**

Aug. 19, 2014 (JP) D2014-018052

Aug. 19, 2014 (JP) D2014-018053

Aug. 19, 2014 (JP) D2014-018054

Aug. 19, 2014 (JP) D2014-018055

(51) **LOC (12) Cl.** ..... **14-04**(52) **U.S. Cl.**USPC ..... **D14/485**(58) **Field of Classification Search**

USPC D14/485-495

CPC G06F 3/048-04897
